UNITED STATES PATENT OFFICE.

M. JOSEPH MANDELBAUM, OF NEW YORK, N. Y.

SIGNALING DEVICE.

1,068,255.

Specification of Letters Patent. Patented July 22, 1913.

Application filed November 7, 1912. Serial No. 729,994.

To all whom it may concern:

Be it known that I, M. JOSEPH MANDELBAUM, a citizen of the United States, and a resident of the city of New York, borough 5 of Manhattan, in the county and State of New York, have invented a new and Improved Signaling Device, of which the following is a full, clear, and exact description.

The object of the invention is to provide 10 a new and improved signaling device more especially designed for use on automobiles and other vehicles, and arranged to enable the chauffeur or other person in charge of the vehicle to display a turn-out sign or a 15 stop sign during the day or night, and to sound an alarm.

For the purpose mentioned, use is made of 20 a casing having a stop-sign compartment and a turn-out sign compartment, the stop sign compartment being provided at the rear with a manually-controlled swing door, a stop sign in the said stop sign compartment, and a manually-controlled turn-out sign mounted to swing sidewise in the said 25 turn-out sign compartment and adapted to project approximately horizontally from the sides of the casing to the right or to the left thereof. Use is also made of electric lamps in the said stop sign compartment to 30 illuminate the stop sign, electric lamps carried by the said turn out sign to move bodily with the same, an electric circuit connected with a source of electrical energy and with the said lamps, and a manually-controlled 35 switch for the said circuit to open and close the same.

A practical embodiment of the invention is represented in the accompanying drawings forming a part of this specification, in 40 which similar characters of reference indicate corresponding parts in all the views.

Figure 1 is a plan view of the signaling device as applied to an automobile; Fig. 2 is a diagrammatic view of the signaling device; Fig. 3 is a perspective view of the casing provided with the turn-out sign and the stop sign, the latter being displayed; Fig. 4 is an enlarged sectional side elevation of the same with the swing door for the stop sign 45 in closed position; Fig. 5 is a transverse section of the same on the line 5—5 of Fig. 4, and showing more particularly the turn out sign; Fig. 6 is an enlarged sectional side elevation of the pivotal end of the turn-out 50 sign; and Fig. 7 is a sectional plan view of the casing of the turn-out sign.

The main frame of the casing A of the signaling device is attached to the vehicle on a desired rear part, preferably, however, to the rear end of the mud guard B' for the 60 left rear wheel of the automobile or other vehicle B, as shown in Fig. 1. The main frame A is provided with a stop-sign compartment C containing a stop sign D, preferably made of glass or other diaphanous material and bearing thereon the legend 65 "Stop," as plainly indicated in Fig. 3. The stop sign D when displayed can be readily read during the day, and during the night the sign is illuminated, preferably by the 70 use of electric lamps E arranged within the compartment C in front of the stop sign D. The rear end of the compartment C is normally closed by a swing door C' so that the 75 stop sign D is not visible, but the said swing door C' is pivoted at its upper end to the upper end of the compartment C and is under the control of the chauffeur or other person in charge of the automobile to permit such person to swing the door C' upward into open position with a view to display the stop sign D.

In order to manipulate the swing door C' the following arrangement is made: From the upper end of the swing door C' extend upwardly-extending arms C² connected with ropes, chains, cables or other flexible connections F passing over pulleys G and under pulleys G' journaled in the compartment C, the flexible connections F thus passing forwardly and out of the casing A to connect with the rear end of a single flexible connection F' passing around guide pulleys G², G³ mounted on the body of the vehicle B, the flexible connection F' then 85 extending forwardly along the vehicle body to finally connect at its forward end with a lever H fulcrumed on the rear face of the dashboard B², so that this lever H is within 90 convenient reach of the chauffeur or other person seated on the seat B³ and in charge 95 of the machine. When the lever H is swung downward a pull is exerted on the flexible connections F', F so that the swing door C' is caused to swing upward into open 100 position to display the stop sign D, as shown in Fig. 3. When the lever H is returned to normal vertical position the swing door C' swings by its own accord into closed 105 position, as shown in Fig. 4.

The main frame or casing A is provided 110 of the compartment C with a com-

partment I open at the sides and extending a distance above the top of the compartment C. Within the compartment I is arranged a turn-out sign J, preferably in the form of an arrow, a pointing hand, or similar sign indicating the direction, and this turn-out sign J is provided at its upper end with a hollow pivot K journaled in the upper portion of the main frame or casing A, 5 the pivot extending longitudinally so as to permit of swinging the sign J from its normal vertical position upward into a horizontal position either to the right or to the left to indicate to a following vehicle that 10 it is intended to turn to the right or to the left according to the direction in which the turn-out sign J is pointing at the time. The turn-out sign J is also under the control of the chauffeur or other operator seated on the 15 seat B³, and for this purpose the following arrangement is made: On the forward end of the pivot K are secured transverse arms K', K² extending in opposite directions from the pivot K, as plainly indicated in 20 Fig. 5, and on the outer ends of the said arms K', K² are fastened links K³, K⁴ engaged by snap hooks L², L³ of cords, ropes, chains, cables or similar flexible connections L, L' extending downwardly and crossing 25 each other (see Fig. 5), and passing under guide pulleys N, N' journaled in the lower portion of the main frame or casing A. The flexible connections L, L' pass around guide pulleys N², N³ mounted on the 30 vehicle body, the flexible connections then passing transversely around another set of guide pulleys N⁴, N⁵ to then extend forwardly to the dashboard B² to connect with levers O and O' fulcrumed on the dashboard 35 B² and located on opposite sides of the lever H previously mentioned. Normally the turn-out sign J hangs downward in a vertical position and is pressed on its opposite sides by springs P, P', and when it is desired 40 to swing the turn-out sign J upward into horizontal position and to the right then the operator swings the lever O downward so that the flexible connection L exerts a pull on the arm K' to turn the pivot K 45 and with it the turn-out sign J so that the latter swings upward into an approximately horizontal position and to the right, as indicated in Fig. 5. As soon as the operator releases the lever O it swings the 50 same back to normal vertical position, and then the spring P' pressing on the turn-out sign J returns the latter to normal vertical position so that the sign is hidden behind the rear casing plate I' of the compartment 55 I. When it is desired to turn out to the left the operator swings the lever O' downward so that a pull is exerted on the flexible connection L' and on the arm K² to turn the pivot K and with it the sign J with a view 60 to swing the latter upward into horizontal 65

position and to the left, thus indicating to a following vehicle that a turn out to the left is intended to be made. When the lever O' is released the spring P will return the turn-out sign J to normal vertical position. 70 The turn-out sign J is colored so as to be readily visible during the day, and during the night it is illuminated so that when displayed it can be readily seen by a following vehicle. The turn-out sign J is provided 75 with a casing J', preferably made of sheet metal, and having a rear plate J² provided with marginal perforations for the passage of light during the night, so that the margin of the arrow appears illuminated and is 80 consequently readily visible to a following vehicle. The top of the casing J' is provided with a wooden block J⁴ in which the pivot K is secured by a screw J⁵ (see Fig. 6) and to the under side of the block J⁴ is 85 attached a depending lamp support Q provided at the rear with the cut-out portions Q', Q² and horizontal shoulders or seats Q³, Q⁴ on which are removably secured depending electric lamps R, R' and a similar electric lamp R² is arranged at the bottom of the support Q. It will be noticed that the electric lights R, R' and R² are immediately in the front of the perforate plate J², and when the lamps R, R' and R² are burning 90 the turn-out sign J is illuminated. 95

The lamp support Q is made hollow for the passage of circuit wires S for the electric lamps R, R', R² and the said circuit wires S pass through a cap K⁶ on the lower 100 end of a branch pipe K⁶ extending through the bottom of the block J⁴ and screwing into the hollow pivot K to allow the circuit wires S to pass forwardly through the hollow pivot K, as plainly indicated in Figs. 4 and 105 6. The circuit wires S are also connected with the electric lamps E in the stop-sign compartment C, and the said electric wires are connected with a battery S' or other source of electrical energy, as indicated in 110 Fig. 2, the battery being located on the vehicle. The circuit wires S are provided with switch contacts S² adapted to be engaged by a switch lever S³ mounted on the dashboard B² adjacent the lever O' so that the switch lever S³ is under the control of the operator to enable the latter to swing the switch lever S³ into closed position during 115 the night so as to light the electric lamps E, R, R', R². It is understood that when the switch lever S³ is in engagement with the switch contacts S² and the door C' is swung open then the sign D is illuminated by the rays of light from the electric lamps E, and the electric lamps R, R' and R² are also 120 125 burning to render the turn-out sign J visible during the night and when swung upward into horizontal indicating position, as previously explained.

An electric alarm T, of any approved con- 130

struction, is preferably mounted on the front portion of the main frame or casing A, and the circuit wires U of this electric alarm are connected with a battery U' or other source of electrical energy located on the vehicle B. The circuit wires U are provided with sets of contact points U², U³ and U⁴ (see Fig. 2) in alignment with the levers H, O and O', so that when any one of the 10 said levers is swung downward by the operator, as previously explained, then the lever makes contact with the corresponding set of contact points U², U³ or U⁴ to close the circuit and to sound the alarm T. Thus when 15 the stop sign D is displayed the alarm T is running, and when the turn-out sign J is swung into pointing position either to the right or to the left the alarm is also sounded, thus warning a following vehicle.

20 The rear portions of the flexible connections L and L' and the parts connecting the same with the pivot K are preferably arranged within a compartment I² forming part of the main frame or casing A and located in front of the stop sign D. By the arrangement described the parts mentioned are protected against rain, snow, dust and the like. The casing A is also provided with a top cap A³ to close the compartments I² 25 and I at the upper ends to protect the turn-out sign J during the time it is in vertical dormant position.

30 Having thus described my invention, I claim as new and desire to secure by Letters Patent:

1. A signaling device for vehicles, comprising a main casing having a compartment open at the sides, a hollow turn-out signal in the form of a pointing sign and 35 having a rear covering plate provided with marginal perforations, a hollow pivot journaled in the said compartment and attached to the said turn-out signal, a lamp support within the said turn-out signal, electric 40 lamps attached to the said support and disposed to illuminate the said marginal perforations, circuit wires connected with the said lamps and extending through the said hollow pivot to connect with a source of 45 electrical energy, and manually-controlled 50 means connected with the said pivot to permit the operator to swing the said turn-out signal from a vertical concealed position in the said compartment into an approximately 55 horizontal display position to project through the open sides of the casing either to the right or left.

60 2. A signaling device for vehicles, comprising a main casing having a compartment open at the sides, a hollow turn-out signal in the form of a pointing sign and 65 having a rear covering plate provided with marginal perforations, a hollow pivot journaled in the said compartment and attached to the said turn-out signal, a lamp support

within the said turn-out signal, electric lamps attached to the said support and disposed to illuminate the said marginal perforations, circuit wires connected with the said lamps and extending through the said hollow pivot to connect with a source of 70 electrical energy, transverse arms on the outer forward end of the said pivot, flexible connections connected with the said transverse arms, and levers under the control of 75 the operator and connected with the said flexible connections to permit the operator to swing the turn-out signal from a vertical concealed position in the said compartment into a sidewise display position to project 80 either to the right or to the left from the compartment.

3. A signaling device for vehicles provided with a turn-out sign having a casing in the form of a pointing sign, the casing 85 having a covering plate provided with marginal perforations, a block in one end of the casing, a hollow pivot extending through the said block from front to rear and having a branch pipe, and a hollow lamp carrier 90 attached to the said block and into which opens the said branch pipe, the said lamp carrier having cut-out portions opposite the said perforate cover plate, electric lamps attached to the said lamp seats, and electric 95 wires connected with the said lamps and extending through the said hollow lamp carrier, the branch pipe and pivot.

4. A signaling device for vehicles provided with a turn-out sign having a casing 100 in the form of a pointing sign, the casing having a covering plate provided with marginal perforations, a block in one end of the casing, a hollow pivot extending through the said block from front to rear and having a 105 branch pipe, a hollow lamp carrier attached to the said block and into which opens the said branch pipe, the said lamp carrier having cut-out portions opposite the said perforate cover plate, electric lamps attached to the said lamp seats, electric wires connected with the said lamps and extending through the said hollow lamp carrier, the branch pipe and pivot, transverse arms on the said pivot, 110 flexible connections connected with the said transverse arms, and levers under the control of the operator and connected with the said flexible connections to permit the operator to swing the turn-out sign from normal vertical position to an approximately horizontal position and projecting to the right or to the left.

5. A signaling device for vehicles, provided with a turn-out sign having a casing 125 in the form of a pointing sign, the casing having a covering plate provided with marginal perforations, a block in one end of the casing, a hollow pivot extending through the said block from front to rear and having a 130 branch pipe and a hollow lamp carrier at

- tached to the said block and into which
opens the said branch pipe, the said lamp
carrier having cut-out portions opposite the
said perforate cover plate, electric lamps
5 attached to the said lamp seats, electric
wires connected with the said lamps and ex-
tending through the said hollow lamp car-
rier, the branch pipe and pivot, springs
pressing the sides of the casing at the pivotal
10 end thereof to normally hold the turn-out
sign in a vertical position, and manually-

controlled means for imparting a swinging
motion to the said turn-out sign to swing the
latter to the right or to the left into an ap-
proximately horizontal pointing position. 15

In testimony whereof I have signed my
name to this specification in the presence
of two subscribing witnesses.

M. JOSEPH MANDELBAUM.
